ROOF DECK

Filed July 22, 1931

INVENTOR:

ALBERT LINDSAY DOERING,

BY *John E. Page*
Attorney.

UNITED STATES PATENT OFFICE

ALBERT LINDSAY DOERING, OF GERMANTOWN, PENNSYLVANIA, ASSIGNOR TO J. S. THORN COMPANY, OF GERMANTOWN, PENNSYLVANIA, A CORPORATION OF PENNSYLVANIA

ROOF DECK

Application filed July 22, 1931. Serial No. 552,357.

My invention relates to roofs and other structures wherein a substantially flat covering is formed of series of sheet metal plates overlapped at their edges like shingles, and particularly to sheet metal clip means for rigidly connecting the overlapped edges of such plates at short distances throughout the area of the covering. For instance, in accordance with specifications of the United States Government, the plates of such roof decks must be securely connected at intervals not exceeding twelve inches.

In the preferred form of my invention chosen for illustration, said plates are corrugated to form a series of longitudinally extending parallel ribs projecting from one side thereof and the ribs include rib entering portions adapted to fit within such a rib on one plate, and in unitary relation with a coupling portion which overlies and secures the edge of an adjoining and overlapping plate, and said clip portions are in integral connection with a base portion which is adapted to be bent around the flanges of an I-beam purlin, or other supporting element of a roof. Such plates are preferably of uniform width, but of different lengths in accordance with the spacing of the purlins, for instance, four feet six inches, seven feet, eight feet, etc.

My invention includes the various novel features of construction and arrangement hereinafter more definitely specified.

In said drawing; Fig. I is a perspective view showing two adjoining plates overlapped and interengaged with a clip embodying my invention.

Fig. II is a perspective view of the complete clip indicated in Fig. I, but in its primary form, before it is bent to overlap the adjoining plates shown in Fig. I.

Fig. III is a fragmentary vertical sectional view of the structure shown in Fig. I, taken in a vertical plane transverse to the ribs on the plates.

Fig. IV is a fragmentary vertical sectional view taken in a plane parallel with said ribs.

In said figures; the roof plates 1 and 2 are overlapped, as indicated at 3, and are simi-

larly corrugated to form a series of parallel ribs 5, 6, and 7 projecting from one face thereof. As indicated, the rib 5 is formed by bending the edge of the metal sheet at right angles so that it will fit within the rib 6 which is U-shaped and at the adjoining edge of another similar plate. The intermediate ribs 7 are similarly U-shaped. Although said ribs 6 and 7 are primarily pressed in the sheet metal of the same dimensions in each of the sheets; the metal is so far elastic that the ribs 6 and 7 upon one sheet may be pressed into the ribs 6 and 7 of another sheet until the sheets are in contact at their upper plane surfaces, as indicated in Fig. I.

As above indicated, I prefer to make said sheets of a standard width of two feet and to connect them at their overlapped edges at intervals of one foot, preferably by clips such as are shown in Fig. II.

As shown in Fig. II, each of said clips includes a base clamp member 9 of heavy sheet metal stamping, say No. 16 gage, the ends of which are adapted to be bent over the edges of the top flanges 10 of the purlin 11, or other supporting beam; to rigidly connect said clip therewith. Said base member 9 is integrally and rigidly connected with the coupling member 12 of the clip, conveniently by welding them together at the spots 12. Said coupling member 12 is formed of thinner metal than said base member, say No. 20 gage, and includes the flange 13 extending vertically with respect to said base member 9 in unitary relation with the flange 14 extending in parallel spaced relation therewith and having the flange 15 bent at right angles thereto and parallel with said base flange 9, in unitary relation with the flange 16 primarily bent vertically at right angles to said flange 15.

Said plate 1 is slid away from the observer in Fig. I over the purlin flanges 10 and with said flange 14 of the clip coupling extending between the opposite side walls of the rib 7 of said plate 1 until said plate 1 is stopped with its inner edge abutting against the bight 17 connecting said flanges 13 and 14. Said plate 1 is held down in that position by the

flange 15 on said clip which overlaps the top surface of said plate 1.

Said plate 2 is then slid toward the observer with its rib 5 outside of the corresponding rib 5 on said plate 1, but with its ribs 6 and 7 inside of the corresponding ribs 6 and 7 on said plate 1 until the edge of said plate 2 abuts against said flange 16 at the junction of the latter with the flange 15 on said clip. Thereupon, said flange 16 is bent downwardly, parallel with said flange 15, to hold down the edge of said plate 2 which overlaps the edge of said plate 1.

Said clips thus have the double function and effect of holding said plates against movement in the direction of the length of said ribs and in rigid connection with said support 11.

In order to distinguish the several portions 20 of the clip, in the following claims, it may be observed that the portion 13 thereof serves as a plate stop flange; that the portion 14 thereof serves as a rib entering flange; that the portion 15 thereof serves as a top holding flange for one of the plates, to wit, the plate 1, and that the portion 16 thereof serves as a top holding flange for the other plate 2.

I prefer to employ such clips in connection 30 with the middle ribs on the overlapped plates throughout the area of the roof deck or similar structure embodying said plates and to use other forms of fastening clips to engage the interlocked edges of said plates.

Therefore, I do not desire to limit myself 35 to the precise details of construction and arrangement herein set forth, as it is obvious that various modifications may be made therein without departing from the essential features of my invention, as defined in the appended claims.

I claim:

1. In a roof deck; the combination with a plate corrugated to form a rib therein, projecting from one face thereof, the opposite walls of the rib being in spaced relation; of another similar plate having one edge overlapping said first plate and with a similar rib entered in said rib of the first plate; and 45 means for detachably rigidly holding said plates in such engaged relation, including a clip having a coupling member inserted in one of the ribs of said first plate, between that rib and the rib of the second plate engaged therewith; said coupling member extending above the top of the interengaged plates and having flanges parallel with said top and engaged with the respective plates.

2. In a roof deck; the combination with a 50 plate corrugated to form a series of parallel ribs therein projecting from one face thereof, the opposite walls of each rib being in spaced relation; of another similar plate having one edge overlapping said first plate and 55 with its ribs entered in the ribs of said first

plate; means for rigidly holding said plates in contiguous relation; including a clip having a coupling member inserted in one of the ribs of said first plate, between that rib and the rib of the second plate engaged therewith; said coupling member extending above the top of the interengaged plates and having flanges parallel with said top and engaged with the respective plates; and a base member on said coupling member, in integral relation therewith, with oppositely projecting ends for bending around a supporting beam.

3. In a roof deck; the combination with a plate corrugated to form a rib therein projecting from one face thereof, the opposite walls of the rib being in spaced relation; of another similar plate having one edge overlapping said first plate and with its rib entering the rib of said first plate; a clip for rigidly holding said plates in such contiguous relation, including a base member which is a strip of heavy sheet metal adapted to be bent at its ends to engage a supporting beam; and a coupling member which is formed of thinner sheet metal including a portion integrally rigidly connected with said base member; said coupling member having a plate stop flange portion extending perpendicularly to the plane of said base member in unitary relation with a rib entering flange portion extending parallel with it and connected with it by a bight at one end; the opposite end of said rib entering flange having a top holding flange extending at right angles to it, parallel with said base member, and in unitary relation with another plate top holding flange at one end thereof; said top holding flanges respectively overlying said plates, at the lapped edges thereof.

4. In a deck plate clip; the combination with a base member of metal including means to engage a supporting beam; of a coupling member formed of ductile metal carried by said base member; said coupling member having an upright plate stop portion with a laterally extending rib entering portion, free from said stop portion at the top and bottom thereof, and connected therewith only at one, upright, end thereof; the opposite end of said rib entering portion having a plate top holding portion extending substantially parallel with said base member.

5. In a deck plate clip; the combination with a base member of ductile metal adapted to be bent at its ends to engage a supporting beam; of a coupling member formed of ductile metal integrally rigidly connected with said base member; said coupling member having a plate stop portion extending transversely to the plane of said base member, and a rib entering portion extending parallel with said stop portion, but free from said stop portion at the top and bottom thereof, and connected therewith only at one, upright, end thereof; the opposite end of said rib en-

tering portion having a plate top holding portion extending parallel with said base member.

6. In a deck plate clip; the combination with a base member which is a strip of ductile sheet metal adapted to be bent at its ends to engage a supporting beam; of a coupling member formed of sheet metal integrally rigidly connected with said base member; 10 said coupling member having a plate stop portion extending transversely to the plane of said base member, and a rib entering portion extending substantially parallel with said stop portion, but free from said stop portion at the top and bottom thereof, and connected therewith only at one, upright, end thereof; the opposite end of said rib entering portion having a plate top holding portion extending substantially parallel with 20 said base member.

7. In a deck plate clip; the combination with a base member which is a strip of ductile sheet metal adapted to be bent at its ends to engage a supporting beam; of a coupling member formed of sheet metal integrally rigidly connected with said base member intermediate of the length of the latter; said coupling member having a plate stop portion extending substantially perpendicularly to 25 the plane of said base member, and a rib entering portion extending substantially parallel with said stop portion but free from said stop portion at the top and bottom thereof, and connected therewith only at one, upright, 30 end thereof; the opposite end of said rib entering portion having a plate top holding portion extending laterally beyond said stop portion and substantially parallel with said base member.

40 8. In a deck plate clip; the combination with a base member which is a strip of ductile metal having means adapted to engage a support; of a coupling member which is formed of sheet metal including a portion welded to 45 said base member; said coupling member having a plate stop flange portion extending perpendicularly to the plane of said base member, in unitary relation with a rib entering flange portion extending parallel with it and 50 connected with it by a bight at one end; the opposite end of said rib entering flange having a plate top holding flange extending at right angles to it and parallel with said base member and in unitary relation with another 55 plate top holding flange at the inner edge thereof primarily extending transversely to said base member and other flanges.

9. In a deck plate clip; the combination with a base member which is a strip of heavy sheet metal adapted to be bent at its ends to engage a supporting beam; of a coupling member which is formed of thinner sheet metal including a portion extending beneath and in contact with said base member and integrally rigidly connected therewith, by a

weld; said coupling member having a plate stop flange portion extending perpendicularly to the plane of said base member, in unitary relation with a rib entering flange portion extending parallel with it and connected with it by a bight at one end; the opposite end of said rib entering flange having a plate top holding flange extending at right angles to it and parallel with said base member and in unitary relation with another plate top holding flange at the inner edge thereof primarily extending transversely to said base member and other flanges.

In testimony whereof, I have hereunto signed my name at Philadelphia, Pennsylvania, this 8th day of July, 1931.

ALBERT LINDSAY DOERING.
